UNITED STATES PATENT OFFICE.

HARVEY M. GERSMAN, OF CHICAGO, ILLINOIS.

METHOD FOR THE PRODUCTION OF EXPANDED TRUSSED BEAMS.

Application filed October 9, 1924. Serial No. 742,712.

This invention relates to a method for the production of expanded trussed beams and more particularly for the production of an expanded beam from an original rolled section, preferably an I-beam section.

The principal object of the invention is to provide a method by which a novel and advantageous form of expanded trussed beam may be produced from an original integral section by procedure of simple and economical character and in which the application of heat is not required and the metal of the blank is not stretched.

A further object is to provide a method by which an expanded trussed-beam produced from an original section which will have sufficient strength for all practical purposes and in which the angle of the struts may be selected as desired without any liability of fracturing.

The accompanying drawings illustrate the practice of the method and an expanded trussed I-beam resulting therefrom.

In said drawings:

25 Figure 1 is an elevation of the slotted blank.
Figure 2 is a section on the line 2—2 of Figure 1.

Figure 3 is an elevation of the blank after the offsetting of the portions which provide 30 the struts.

Figure 4 is a section on the line 4—4 of Figure 3.

Figure 5 is an elevation of the blank after expansion.

35 Figure 6 is a section on the line 6—6 of Figure 5.

Figure 7 is an elevation of the completed beam.

40 Figure 8 is a section on the line 8—8 of Figure 7.

The blank from which the expanded beam is produced is preferably of the form shown in Figures 1 and 2, which consists of a rolled I-beam shape of the usual or any desired section having a central planar web 1 and top and bottom flanges 2 and 3. The web 1 is slotted in characteristic fashion to provide for expansion in accordance with the invention. Thus the web is provided with parallel 45 diagonal slits 4 which extend from points near one flange to points near the other and with short alining longitudinal slits 5 which, as shown, extend between corresponding ends of adjoining slits 4. Thereby the slits 4 are 50 connected in successive pairs adjacent one of the flanges with the result that the metal be-

tween the slits not connected has the form of continuous strands 6 and the metal between the connected slits has the form of interrupted or discontinuous strands, that is to say of tongues 7 which alternate with the strands 6. As shown and preferred the slits 4 terminate at points short of the flanges, thereby leaving beyond the slits solid web portions 1^a and 1^b but, if desired, the slits 4 may be continued right up to the flanges and these may be made of such thickness as may be deemed advisable. The strands 6 are laterally offset so as to lie in a common plane at the same side of the mean plane of the web. 60 This offsetting of the strands is accomplished by a corrugating operation in the manner disclosed in my pending application, Serial No. 642,872, that is to say the web is longitudinally channelled or corrugated in the portions constituted by the strands, the slits extending into and along the sides of the channel or corrugation. The tongues 7 which, as shown, project from the solid portion 1^a, are in like manner bent so as to lie in a common 65 plane at the opposite side of the mean plane of the web. The corrugating and bending operations by which the strands and tongues are thus laterally offset whereby the blank has the form shown in Figures 3 and 4 may 70 be performed in connection with the slitting or at a later stage. The strands and tongues are also preferably curved between their ends so as to have convex faces adjacent the mean plane of the web, as shown in Figure 75 4, and such curving may be done at the time of slitting or at a later stage.

The blank is now ready for expansion and this is accomplished by moving the flanges in relatively opposite directions while maintaining their angular relation to the mean plane of the web whereby the strands are caused to approach more nearly to perpendicular positions, as shown in Figure 5. Such expansion of the blank follows generally the procedure outlined in my said pending application, Serial No. 642,872 but produces no change in the positions of the tongues 7; and the beam is completed by bending the tongues in the general direction of their common plane so as 90 to cause them to extend oppositely, that is to say in intersecting relation to the strands as produced by the expansion, after which the free ends of the tongues are suitably secured, as by spot welding, to the adjacent solid section of the web, the completed beam being 95 shown in Figures 7 and 8. Such bending of 100 105 110

the tongues may be effected simultaneously with the expansion or at a later stage. If desired, and for the purpose of providing a true lattice truss, the tongues and strands may 5 be suitably secured, as by spot welding, to one another at their points of intersection, as indicated at 8 in Figure 7.

It will be obvious that the strands may be bent in the direction of their common plane 10 to greater or less degree and that the degree to which the tongues are bent in their common plane will depend on the degree to which the strands are bent. As shown the strands have been bent to positions short of perpendicular and the tongues have been bent through and beyond perpendicular but if desired the strands may be bent through and beyond perpendicular in which case the tongues will be bent to positions suitably 15 short of perpendicular.

It will be observed that the angle of the struts are not limited by the ductility and elasticity of the metal and that any angle is practical without liability of fracture.

25 Instead of locating the short slits 5 at the ends of the diagonal slits 4 they may be located as desired at points along the length of the slits 4, for example at midway points. Such location of the slits 5 will result in the 30 discontinuous strands each being in the form of a pair of originally alining tongues projecting from the respective solid portions 1^a and 1^b or from the respective flanges 2 and 3 in case the solid portions are not employed. 35 After expansion of the continuous strands as above described the originally alining tongues which, during expansion, have become relatively longitudinally offset, are bent back into alining relation and their ends connected by welding, the same welding operation being available to connect them to the 40 continuous strands which they intersect.

Having fully described my invention, I claim:

45 1. A method for the production of an expanded trussed beam from a structural section having oppositely located flanges and a solid planar web integral with the flanges which consists in slitting the web to provide 50 parallel diagonal continuous strands and interrupted strands parallel to and alternating with the continuous strands, in effecting the expansion of the web, in bending the interrupted strands from the positions in which they are left by the expansion into intersecting relation to the continuous strands and parallel relation to one another and securing the interrupted strands at their points of interruption to adjacent parts of the web.

60 2. A method for the production of an expanded trussed beam from a structural section having oppositely located flanges and a solid planar web integral with the flanges which consists in slitting the web to provide 65 parallel diagonal continuous strands and in-

terrupted strands parallel to and alternating with the continuous strands, in relatively laterally offsetting the continuous and interrupted strands, in effecting the expansion of the web, in bending the interrupted strands from the positions in which they are left by the expansion into intersecting relation to the continuous strands and parallel relation to one another and securing the interrupted strands at their points of interruption to adjacent parts of the web.

3. A method for the production of an expanded trussed beam from a structural section having oppositely located flanges and a solid planar web integral with the flanges which consists in slitting the web to provide parallel diagonal continuous strands and interrupted strands parallel to and alternating with the continuous strands, in effecting the expansion of the web, in bending the interrupted strands into positions in which they may be secured at their points of interruption, and securing the bent interrupted strands at their points of interruption to adjacent parts of the web.

4. A method for the production of an expanded trussed beam from a structural section having oppositely located flanges and a solid planar web integral with the flanges which consists in slitting the web to provide parallel diagonal continuous strands and interrupted strands parallel to and alternating with the continuous strands, in relatively laterally offsetting the continuous and interrupted strands, in effecting the expansion of the web, in bending the interrupted strands into positions in which they may be secured at their points of interruption, and securing the bent interrupted strands at their points of interruption to adjacent parts of the web.

5. A method for the production of an expanded trussed beam from a structural section having oppositely located flanges and a solid planar web integral with the flanges which consists in providing parallel diagonal slits in said web with the slits of successive pairs connected by longitudinal slits, thereby to provide continuous parallel strands integral at both ends with the web and interrupted strands alternating with the continuous strands, in relatively laterally offsetting the continuous and interrupted strands, in relatively shifting the flanges to expand the portion of the web constituted by the strands, and in bending the interrupted strands to extend oppositely and in intersecting relation to the continuous strands and connecting the interrupted strands at their points of interruption to adjacent parts of the web.

6. A method for the production of an expanded trussed load bearing member from a structural section having a planar web which consists in providing parallel diagonal slits in said web with solid portions beyond the slits and the slits of successive pairs connect-

ed by longitudinal slits, thereby to provide continuous parallel strands integral at both ends with said solid portions and interrupted strands alternating with the continuous strands, in relatively laterally offsetting the strands and the tongues, in relatively shifting the solid portions longitudinally in their common plane to expand the portion of the web constituted by the strands, and in bending the interrupted strands to positions wherein they may be attached at their points of interruption to adjacent parts of the web and in attaching said interrupted strands at their points of interruption to adjacent parts of the web.

7. A method for the production of an expanded trussed load bearing member from a structural section having a planar web which consists in providing parallel diagonal slits in said web with the slits of successive pairs connected by longitudinal slits, thereby to produce continuous parallel strands integral at both ends with the web and interrupted strands alternating with the continuous strands, in offsetting the continuous strands and the interrupted strands laterally at opposite sides of the mean plane of the web, in relatively shifting the flanges to expand the portion of the web constituted by the continuous strands, and in bending the interrupted strands to positions wherein they may be attached at their points of interruption to adjacent portions of the web and in attaching the bent interrupted strands at their points of interruption.

8. A method for the production of an expanded trussed load bearing member from a structural section having a planar web which consists in providing parallel diagonal slits in said web with the slits of successive pairs connected by longitudinal slits, thereby to produce continuous parallel strands integral at both ends with said web and interrupted strands alternating with the continuous strands, in forming a longitudinal channel in the portion of the web constituted by the continuous strands with the ends of the slits extending into the sides of the channel, thereby to offset the continuous strands laterally with respect to the mean plane of the web, in relatively shifting the flanges to expand the portion of the web constituted by the continuous strands, and in bending the interrupted strands to positions wherein they may be attached to adjacent portions of the web at their points of interruption and in attaching the bent interrupted strands at their points of interruption to adjacent portions of the web.

9. A method for the production of an expanded trussed load bearing member from a structural section having a planar web which consists in providing parallel diagonal slits in said web with the slits of successive pairs

connected by longitudinal slits, thereby to produce parallel strands integral at both ends with the web and interrupted strands alternating with the continuous strands, in forming a longitudinal channel in the portion of the web constituted by the continuous strands with the ends of the slits extending into the sides of the channel, thereby to offset the continuous strands laterally with respect to the mean plane of the web, in laterally offsetting the interrupted strands at the opposite side of the mean plane of the web, in relatively shifting the flanges to expand the portion of the web constituted by the continuous strands, and in bending the interrupted strands to positions wherein they may be attached to adjacent portions of the web at their points of interruption and in attaching the bent interrupted strands at their points of interruption to adjacent portions of the web.

10. A blank for use in the production of an expanded trussed load bearing member consisting of a rolled structural section having a planar web provided with parallel diagonal slits with the slits of successive pairs connected by longitudinal slits, thereby to provide continuous strands and interrupted strands alternating with the continuous strands.

11. A blank for use in the production of an expanded trussed load bearing member consisting of a rolled structural section having a planar web provided with parallel diagonal slits with the slits of successive pairs connected by longitudinal slits, thereby to provide continuous strands and interrupted strands alternating with the continuous strands, the continuous strands and the interrupted strands being relatively laterally offset.

12. In the production of an expanded trussed load bearing member from a structural section having a planar web, providing parallel diagonal slits in said web with the slits of successive pairs connected by longitudinal slits thereby to produce continuous strands and interrupted strands alternating with the continuous strands, relatively laterally offsetting the continuous strands and the interrupted strands, and relatively moving the flanges to alter the angle and increase the mutual spacing of the continuous strands.

13. A blank for use in the production of an expanded trussed load bearing member consisting of a rolled structural section having a planar web provided with parallel diagonal slits and solid portions beyond the ends of the slits with the slits of successive pairs connected by longitudinal slits, thereby to provide continuous strands and interrupted strands alternating with the continuous strands.

In testimony whereof I affix my signature.

HARVEY M. GERSMAN.
